DESIGN FOR A BRACKET FOR A STEERING
WHEEL TURNING KNOBWilliam H. Snow, Chicago, Ill., assignor to Snow-
Craggs Corporation, Chicago, Ill., a corpora-
tion of Illinois

Application February 27, 1937, Serial No. 67,893

Term of patent 14 years

To all whom it may concern:

Be it known that I, William H. Snow, a citizen of the United States, residing at Chicago, in the county of Cook and State of Illinois, have invented a new, original, and ornamental Design for a Bracket for a Steering Wheel Turning Knob, of which the following is a specification, reference being had to the accompanying drawing, forming a part thereof.

Figure 1 of the drawing is a perspective of a bracket for a steering wheel turning knob showing my new design;

Figure 2 is a plan view of the bracket;
Figure 3 is a side elevational view; and
Figures 4 and 5 are inner and outer end ele-
vational views respectively.

I claim:

The ornamental design for a bracket for a steering wheel turning knob, substantially as shown.

WILLIAM H. SNOW.
